Patented Jan. 10, 1956

176,612

WOMAN'S SWEATER

Erwin B. Jackman, Brooklyn, N. Y.

Application January 31, 1955, Serial No. 34,297

Term of patent 14 years

(Cl. D3—4)

The figure is a plan view of a woman's sweater in undraped position showing my new design. Both faces of the sweater are identical in appearance.

I claim:

The ornamental design for a woman's sweater, substantially as shown and described.
